ELIHU SPENCER, OF OTTAWA, CANADA.

Letters Patent No. 83,563, dated October 27, 1868.

IMPROVEMENT IN STATION-INDICATORS.

The Schedule referred to in these Letters Patent and making part of the same.

To all whom it may concern:

Be it known that I, ELIHU SPENCER, of Ottawa, in the Dominion of Canada, have invented certain new and useful Improvements in Station-Indicators for Railways; and I do hereby declare that the following is a full, clear, and exact description thereof, which will enable others skilled in the art to make and use the same, reference being had to the accompanying drawings, forming a part of this specification.

This invention relates to certain new and useful improvements in station-indicators for railways, which improvements are more especially applicable to an implement for the above purpose which was patented by me, December 31, 1867.

The present invention consists in the application of a bell to the device, so arranged that it will be automatically sounded each time the device is operated after leaving each station, to exhibit the name of a succeeding station.

The invention also consists in the application of a stop to the device, to prevent the latter being casually turned or moved in the wrong direction by the brakeman or other attendant.

The invention also consists in a modification of the construction of the device, whereby a candle or lamp may be applied to illuminate the names of the stations, so that they will be equally as discernible at night as during the day.

The invention consists, finally, in a peculiar application of cards to the front of the device, whereby passengers may be notified where they are required to change cars, the stations where refreshments may be taken, &c., &c.

In the accompanying sheet of drawings—

Figure 1 is a front view of my invention, partly in section.

Figure 2, a side view of a portion of the same.

Figure 3, an enlarged and detached plan or top view of the bell-hammer mechanism.

Figure 4, a transverse vertical section of the card-attachment, taken in the line *x x*, fig. 1.

Similar letters of reference indicate corresponding parts.

A represents a rectangular box, which may be of any suitable dimensions, the upper part, *a*, being a lid or cover, which is attached to the lower part, *b*, by hinges or joints.

In the top part of *b* there is placed a shaft, on which are secured two hexagonal heads, *B B*, one of the journals of the shaft having a square formed on it, to receive a key, *C*, by which the shaft and its heads are turned.

A series of plates, *c*, connected together by links or joints, work or are fitted on the heads *B B*, the width of the plates being equal to the length of the sides of the heads. These plates *c* may be constructed of tinned plates, or thin sheet-metal, and are cut out at their centres, leaving a large open space in each plate, and these spaces are covered with muslin, or any suit-

able cloth or fabric, *d*, which is transparent or semi-transparent. The names of the stations are printed or painted on these fabrics *d*, and by placing a candle or lamp, *D*, at one side of the box *A*, within a suitable covering, *a*, and having a hole in the side of the box for the rays of light to enter, the names of the stations may be seen equally as well at night as during the day, and be conspicuous from all parts of a car.

The names of the stations are exhibited through a proper opening in the front of the box *A*, and, with the exception of the perforating of the plates *c*, and covering the perforations with a cloth or fabric, semi-transparent, in order to render the names of the stations visible at night, the mechanism of this part of the device is substantially the same as in the original patented device.

To the inner surface of one end of the box *A* there is attached an adjustable or sliding bar, *E*, (see, more particularly, fig. 2,) having upright or vertical ends, *e e*. By sliding this bar *E* either to the right or left, the ends *e* are made to serve as stops, and prevent the heads *B* from being turned in the wrong direction, in consequence of projections, *f*, on the heads coming in contact with an end, *e*. One end, *e*, of the bar can only be adjusted in line with the projections *f* at once, and hence the heads *B* may always be turned in one direction, and, by properly adjusting the bar *E*, only in the right direction.

It will be understood, of course, that the movement of the heads is reversed at the commencement of each route from that of the previous route.

F is a bell, which is placed on the top of the box *A*. This bell is struck by two hammers, *G G*, the rods *g* of which are attached to right-angular plates *H H*, the latter working on pivots, *h*, and having the ends of a spring, *I*, in contact with them. (See fig. 3.)

This spring *I* may be constructed of a single rod, bent around a pin, *i*, in a frame, *K*, in the upper part of the lid of the box *A*, and in which frame a lever, *K*, is fitted, said lever having its fulcrum at *j*. The inner edges of the plates *H H* are formed with notches, to receive the outer parts of the springs *I*.

The long arm of the lever *K* is actuated by projections, *l*, on one of the heads *B*, and the short arm of said lever acts against one of the plates *H*, the movement of which is resisted by the spring *I*, and when the projection *l* of the head has passed the long arm of the lever *K*, the spring *I* forces the lever back to its original position, and the hammer *G* against the bell, producing the necessary sound.

It will be seen that this bell-striking mechanism is a duplex or double one. This is necessary, in order that the lever *K* may be operated in either direction, so that the bell may be sounded when the heads *B* are turned in either direction.

To the front side of the box *A* there is attached a horizontal rod, on which a series of flaps, *L*, is fitted, and allowed to swing freely, the flaps being attached

by hinges or joints to the rod. These flaps have a tendency to hang down, by their own gravity, and on their inner sides or surfaces the instructions necessary to be given the passengers in connection with any station are pasted or printed, as, for instance, "Twenty minutes for dinner," "Change cars," &c., &c.

In order to expose or exhibit these instructions, one flap, in each case, is raised, and retained in a raised position by a drop-catch, M. (See fig. 4.)

Having thus described my invention, What I claim as new, and desire to secure by Letters Patent, is—

1. The cutting out or otherwise constructing the plates c, so as to form frames, over or on which a transparent or semi-transparent fabric, d, is secured, having the names of the stations upon them, in combination with a candle, lamp, or other light D, placed at

one side of the box A, and arranged so as to throw the rays of light within the same, substantially as and for the purpose specified.

2. The adjustable or sliding bar or stop E, arranged and applied in the manner substantially as and for the purpose set forth.

3. The bell-operating mechanism, composed of the lever K, spring I, right-angular plates H, H, and hammers G, G, all arranged to operate by the turning of the heads B, substantially as and for the purpose specified.

4. The flaps L, when applied to the box A, and used in connection with the drop-catch M, substantially as and for the purpose specified.

ELIHU SPENCER.
